(57) **CLAIM**

The ornamental design for the power cutter, as shown and described.

DESCRIPTION

FIG. 1 is a perspective view of a power cutter in accordance with an embodiment of the present invention;

FIG. 2 is a back view of the power cutter of FIG. 1;

FIG. 3 is a front view of the power cutter of FIG. 1;

FIG. 4 is a left side view of the power cutter of FIG. 1;

FIG. 5 is a right side view of the power cutter of FIG. 1;

FIG. 6 is a top view of the power cutter of FIG. 1; and,

FIG. 7 is a bottom view of the power cutter of FIG. 1.

The broken lines of the power cutter in FIGS. 1-7 form no part of the claimed design.
